UNITED STATES PATENT OFFICE.

BENEARD SCHNEPP, OF LOUISVILLE, KENTUCKY.

OFF-BEARING POLE FOR LEATHER SIDES.

SPECIFICATION forming part of Letters Patent No. 470,872, dated March 15, 1892.

Application filed October 2, 1891. Serial No. 407,525. (No model.)

To all whom it may concern:

Be it known that I, BENEARD SCHNEPP, a citizen of the United States, residing at Louisville, in the county of Jefferson and State of Kentucky, have invented certain new and useful Improvements in Off-Bearing Poles for Leather Sides; and I do declare the following to be a full, clear, and exact description of the invention, such as will enable others skilled

in the art to which it appertains to make and use the same, reference being had to the accompanying drawings, and to the letters of reference marked thereon, which form a part of this specification.

15 My invention relates to devices for carrying and hanging sides of leather; and it consists in the novel construction of a carrying-pole which is especially adapted to be used in connection with the leather-hanging frames for

20 which a patent, No. 457,014, was allowed me on the 14th of January, 1891, but which may be used independent of that device.

Sides of leather after being set by the finishers are hung up to dry. They are generally carried by means of hooks having hand-rings attached, and in such cases it is necessary to cut three holes near the upper edge of each side, one at each end for hanging the side and one in the middle for carrying it. It

30 is then carried by inserting one ringed hook in an end hole and one in the middle. In this case the hide will fold over, and this folding makes a crease which is difficult to smooth out. The hides are then hung by strings attached to the hanging posts or frames, which are passed through the end holes and tightened. Sometimes a hanging-pole is nailed along the straight edge of the side, which is stretched along the pole, and the pole is then

40 placed on suitable supports with the side attached. A pole provided with mortised blocks having hooks attached has also been used and the pole placed on a frame with the hide attached. These plans are all objectionable and

45 expensive. Cutting three holes in the side wastes leather and using nails injures the leather and the poles and wastes both leather

and nails, and the necessity for using one pole with each side is expensive.

The object of my invention is to provide an improved pole which dispenses with the middle hole in the leather side and with the use of nails and which can be used with many sides of leather. I accomplish this by the means hereinafter described, and specifically set forth in the claim.

In the drawings, Figure 1 is a perspective view of my carrying-pole. Fig. 2 is a similar view with the slotted end of my pole broken away, so as to show the ratchet-bar.

50 A represents the pole, which is made larger in the middle and tapering toward each end.

A' represents a notch in one end of the pole to receive the ring of a carrying-hook, the lower prong of said notch being longer than

60 the upper.

B is a metal bar ratcheted on its upper edge, which is fitted in a longitudinal slot in the other end of the pole and of a length corresponding to the usual differences in the sizes 70 of hides. This bar is held in the slot by two bolts *a a*, passing through it and through the pole from side to side. The bolt next the inner end of the slot acts as a pivot and the other works in a transverse slot *b* in the bar, 75 which allows the ratchet-bar to sink down into the slot till the points of its teeth are nearly flush with the pole.

C is a steel spring having one end bolted to the solid part of the lower side of the pole and 80 the other end bearing on the back of the ratchet-bar, pressing it up against any weight that may be placed on it.

b' is a toothless prolongation of the ratchet-bar extending beyond the slotted end of the 85 pole.

In carrying a side of leather with this pole the ring of the hook in one end of the side is put over the notch A'. The ring of the hook in the other end of the side is passed over the 90 end having the ratchet-teeth in it and is lodged in the tooth that suits the size of the hide. In delivering the hide at the hanging frame it is convenient to lower the ratchet-teeth till

they are flush with the pole, in order that the ring may come off more easily, which may be conveniently done by pressing the projection b' against the hanging-frame or some firm object.

Having thus described my invention, what I claim as new is—

In an off-bearing pole for leather sides, the combination of the pole A, having a longitudinal slot in one end and a notch A' in the other,

the ratchet-bar B, having the prolongation b' , and the transverse slot b , and the spring C, substantially as described, and for the purpose specified.

In testimony whereof I affix my signature in presence of two witnesses.

BENEARD SCHNEPP.
